AUTOMATIC YARN TENSION CONTROL
MECHANISM FOR KNITTING MACHINES

Vernon Thomas Stack, Walkertown, N. C.

Application May 4, 1949, Serial No. 91,338

10 Claims. (Cl. 66—146)

1

This invention relates to yarn tension control mechanism for knitting machines, particularly circular knitting machines of the kind commonly employed in the commercial production of seamless hosiery and the like.

Full length or ladies' stockings successively knitted upon circular machines as ordinarily constructed, differ considerably in length, this irregularity being due to the lack of proper control of the yarn as it is fed to the needles and consequent formation, in individual courses, of loops which differ in size and contour and which often create an undesirable streaked appearance in the stockings.

The chief aim of my invention is to overcome the above drawbacks, that is to say: to make possible the more accurate control of yarn feeding in such knitting machines with a view toward determining formation of the fabric loops which are uniform throughout individual courses, and thereby insure production of successive stockings which will all be of the same length and which will not be marred by shadow lines, streaks or other blemishes, nor require subsequent matting or pairing as heretofore.

The foregoing objective is attained in practice, as hereinafter more fully disclosed, through provision of a relatively simple and reliable automatic yarn tension control mechanism which, in its preferred form, includes an electric motor adapted, through speed reduction gearing and linkages, to actuate a yarn tensioning means. The flow of electric current to the motor is governed by a reversing detector switch operated through a rider element from the sinkers or web holders of the knitting machine in such a way as to bring about compensative slackening of the yarn in the event that the fabric loops on the needles tend to tighten and force the sinkers outward, and compensative increase in the yarn tension as the sinkers recede inwardly when the fabric loops tend to become larger during the formation of individual fabric courses.

Other objects and advantages will appear from the following detailed description of the attached drawings, wherein Fig. 1 is a broken out view in elevation, of sufficient of a standard circular stocking knitting machine conveniently embodying my improved yarn tension control mechanism.

Fig. 2 is a fragmentary view in plan on a somewhat larger scale looking as indicated by the angled arrows II—II in Fig. 1, and showing the reversing detector switch. Also shown in this figure diagrammatically are the electrical connections between the detector switch and the other parts of the control mechanism.

2

Fig. 3 is a fragmentary view of the machine, partly in elevation and partly in vertical section, on a still larger scale taken as indicated by the angled arrows III—III in Fig. 2.

Fig. 4 is a detail view in cross section taken as indicated by the angled arrows IV—IV in Fig. 3.

Fig. 5 shows the electric motor, and the parts immediately associated therewith, in top plan.

Fig. 6 is a sectional view taken as indicated by the angled arrows VI—VI in Fig. 5.

Figs. 7 and 8 are perspective views showing the component parts of two limit switches incorporated in the tension control mechanism.

The needle cylinder 10 of the circular knitting machine herein illustrated in Fig. 1 for convenience of exemplifying my invention, is mounted as usual on a bed 11 supported by machine frame 12, and surrounded adjacent its top by a sinker ring 13. Through suitable mechanism (not shown), the needle cylinder 10 is rotated and oscillated at different times during the knitting as required in the production of seamless hosiery. The yarn feed finger indicated at 15 is swingable into and out of active position about a pin 16 in an upward projection 17 of the latch guard ring 18 of the machine; and the knitting yarn Y is supplied from a cone C and, enroute to said feed finger, passes through guide eyes 20 and 21 respectively on an arm 22 extending laterally from the yarn tree post 23, and on the latch guard ring 18. In the interval between the guides 20 and 21, the yarn Y passes over the restraining rolls 24 of a tensioning device 25, said rolls being revolvably supported in longitudinally spaced upstanding lugs of a bracket 26 which is secured to the post 23, with capacity for angular adjustment, by a clamp screw 27. Fulcrumed on studs 28 at opposite ends of the bracket 26, is a rocker 29 having three arms with eyes 30 at their swinging ends through which the yarn is passed and by which it is depressed between and beyond the rolls 24. The pattern shaft 31 of the machine is intermittently rotated as usual so as to be turned through a complete revolution during each knitting cycle, and secured thereto is the usual belt shipper cam disk 32. Slidable in radial grooves of the sinker ring 13 are sinkers or web holders S (Figs. 2 and 3) which cooperate with the needles N of the machine in the well known manner in stitch formation, and which are pressed

inwardly toward the needles by an encircling spring band 33 so as to yieldingly engage the sinker wale loops of the fabric. The sinker actuating cams (not illustrated) are carried by a cap 34 which overlies the sinker ring 13, and which is held against rotation during round and round knitting but allowed a limited independent

rotary play during reciprocatory knitting likewise in the well known way.

The automatic yarn tension control mechanism, with which the present invention is more especially concerned, includes a direct current electric motor which is indicated at 35. As shown, the motor 35 is enclosed in a housing 36 affixed to the post 23 behind the tensioning means 25 as best seen in Fig. 1. Through a spur pinion 37 and an intermeshing spur wheel 38 (Figs. 5 and 6), the motor 35 is arranged to drive a shaft 39 supported for rotation in a bearing 40 within the channel hollow of a U-shaped bracket 41 secured shaft to the housing 36. A worm 42 on the shaft 39 is in turn arranged to drive a worm wheel 43 on a transverse shaft 45 whereof the ends are journaled in the opposite side portions 46 and 47 of the channel bracket 41. Keyed to the shaft 45 is an arm 48 which, by means of a link 49, is connected to an arm 50 (Fig. 1) on the rocker 29 of the tensioning means 25. The swing of arm 48 is restricted to a prescribed range by limit switches 51 and 56 supported within the channel hollow of the bracket 41, and arranged to be automatically opened to interrupt current flow to the motor 35 when said arm is moved up and down beyond said range as will be more fully explained later. The fixed contact of switch 51 is in the form of an angular lug 52 which is secured, with interposition of insulation, to the outer flange 46 of bracket 41 at 53. The movable contact of switch 51 is in the form of a finger 54 fulcrumed at 55 with interposition of insulation, and having a pendent projection 54a in the path of arm 48. The fixed contact of limit switch 56 is likewise in the form of a lug 57 secured, with interposition of insulation, to the bottom web of the bracket 41 at 58, and the movable contact of said switch is in the form of a finger 59 fulcrumed, likewise with interposition of insulation, at 60 on the upstanding ear 57a of the aforesaid lug 57. As shown, the tail 59a of contact finger 59 extends into the path of a radial projection 61 on shaft 45.

Supply of electric current to the motor 35 to drive it in one direction or the other is governed by a reversing detector switch comprehensively designated 65 in Figs. 1-4. This detector switch 65 has a contact arm 66 which is subject to an adjustable spring 67, and which is pivoted on an upstanding stud 68 in an elongate box-like casing 69 of non-conductive material such as hard rubber, so as to be swingable between a pair of fixed contacts 70 and 71 at opposite sides of said casing. By means of the regulating screw at 72, the casing 69 can be bodily adjusted about the stud 68 as an axis for a purpose also later explained, the end of said screw bearing against the bracket 80 as shown in Fig. 2. The detector switch 65 is affixed to a slide 73 so as to be constrained to endwise movement in a bracket 74 disposed radially of a needle cylinder 10 and secured to another fixed post 75 on the machine. A spring-pressed stud 76 (Fig. 3) acting upon a downward projection 73a at the outer end of slide 73, tends to retract the detector switch 65 from its active position which is determined by engagement of an adjustable stop screw 77 in said downward projection, with the outer edge of the bracket 75. The detector switch 65 is normally maintained in active position by means including a bell crank lever 78 which is pivoted at 79 on a bearing bracket 80 reaching laterally from the post 75. The pendant arm 78a of the bell crank lever 78 presses against the downward projection 73a of slide 73,

while the horizontal arm 78b of said lever is connected, by a Bowden wire 81, to a finger 82 (Fig. 1) pivoted to a bracket 83 on the base plate 84 of the machine. As shown, the finger 82 bears against the edge of cam disk 32 which, for the purposes of my invention, is provided with two circumferentially spaced depressions 85 and 86.

Normally, with the detector switch 65 in active position as in Figs. 2 and 3, the short extremity 66a of its movable contact 66 bears against the protruding outer convex edge of a segmental rider element 90 which is lodged in a slot 91 in the side of a sinker cap ring 34, with its concave inner edge bearing against the butt ends of a plurality of the sinkers S. The rider element 90 is pivoted about a stud 92 on the sinker cap ring 13, and its swing is limited by coaction of a notch 90a in its outer end with a stop stud 93.

Direct current for operation of the motor 35 may be obtained, as diagrammatically shown in Fig. 2, from an alternating current source by use of a transformer 95 having a split secondary whereof the two coil sections are designated 96 and 97. The current induced in the coils 96 and 97 at suitably reduced voltage is converted to direct current by rectifiers conventionally indicated at 98 and 99. Extending from the rectifier 98 to one brush of the motor 35, is a conductor 102 in which a master switch 103 is interposed, the other motor brush being connected by another conductor 105 to the movable contact 66 of detector switch 65. Leading from the rectifier 99 to the fixed contact 52 of limit switch 51 is a conductor 106. The movable contact 54 of limit switch 51 is connected in circuit with the fixed contact 70 of detector switch 65 through still another conductor 107. The other fixed contact 71 of the detector switch 65 is in turn connected to the fixed contact 57 of limit switch 56 by a conductor 108, and the movable contact 59 of the latter switch to the terminal 109 of the secondary coil section 96 of transformer 95 by a conductor 110.

By reason of the described construction and arrangement of the constituent parts of my improved automatic yarn tension control mechanism, it will be seen that, upon the slightest outward movement of the sinkers S in the event of any tendency of the loops on the needles N to tighten, the rider element 90 will be correspondingly shifted and the movable contact 66 of detector switch 65 swung from its normal neutral position into engagement with the fixed contact 70. As a consequence, current will flow to the motor 35 from the transformer coil 97 by way of the terminal 101, conductor 106, limit switch 51, conductor 107, the fixed and movable contacts 70 and 66 of detector switch 65, conductor 105 and conductor 102 to drive said motor in one direction, whereby, through the speed reduction gearing and linkages associated with said motor, the fingers 30 of the tensioning device will be momentarily raised to relieve the tension on the yarn Y. On the other hand, in the event that the loops on the needles should tend to slacken and allow the sinkers to recede toward the needles, the rider element 90, in following up, will cause the movable contact 66 of detector switch 65 to be swung from its normal neutral position into engagement with fixed contact 71 of said switch. When this action takes place, current will flow in the opposite direction from the transformer coil 96 to the motor 35 by way of conductor 110, limit switch 56, conductor 108, 75 fixed and movable contacts 71 and 66 of detector

switch 65 and conductor 105, whereby, through the gearing and linkages associated with said motor, the fingers 30 of tension device 25 will be swung downward to momentarily increase the tension on the yarn. In this way, the tension of the yarn will be compensatively varied for maintenance of a uniform loop size during the knitting of successive courses of the fabric. If the yarn should break and the fingers 30 of the tensioning device 25 for this or any other reason swing in either direction beyond the range prescribed by the limit switches 51 and 56, the latter will be opened to interrupt current flow to the motor 35. Preparatory to the heel and toe knitting phases of the machine, the detector switch 65 is bodily retracted to inactive position by pressure of the spring-backed plunger 76 (Fig. 1) upon the slide 73 as the pull on the bell crank lever 78 is relieved when the finger 82 falls into the peripheral notches 85 and 86 of cam 32 on the pattern shaft 31 of the machine. The mechanism may be rendered inoperative when its use is not desired or required, by opening the master switch 103 as will be readily understood.

The position of the end 66a of the switch element 66 relative to the rider element may be accurately varied through adjustment of the housing 69 about the stud 68 by means of the screw 72 to predetermine the size limits of the smallest and largest loops made during a knitting cycle of the machine.

Having thus described my invention, I claim:

1. Automatic yarn tension control mechanism for a knitting machine having a plurality of independent needles, individually cooperative sinkers spring-urged toward the needles, and a means for tensioning a knitting yarn enroute to the needles, said control mechanism including a detector adapted to be influenced by the sinkers in the event of any tendency of the fabric loops formed by the needles to tighten or slacken, and interposed means for actuating the tensioning means to compensatively increase or decrease the tension on the yarn for maintenance of a uniform loop size in individual courses of the fabric produced by the machine.

2. Automatic yarn tension control mechanism, according to claim 1, wherein the tensioning means comprises a pivoted element in engagement with the yarn in the interval between two yarn guides; and further including means for rendering the control mechanism inoperative upon movement of said pivoted element beyond prescribed limits in opposite directions.

3. Automatic yarn tension control mechanism for a knitting machine having a plurality of independent needles, individually cooperative sinkers spring-urged toward the needles, and means for tensioning a knitting yarn enroute to the needles, said control mechanism including a reversible motor for actuating the yarn tensioning means, a rider element bearing against and adapted to be influenced by movement of the sinkers in the event of any tendency of fabric loops on the needles to tighten or slacken, a detector arranged to be actuated by the rider element, and interposed means whereby the motor is operated in one direction or the other to correspondingly actuate the tensioning means and thereby compensatively vary the tension on the yarn for maintenance of a uniform loop size in individual courses of the fabric produced by the machine.

4. Automatic yarn tension control mechanism, according to claim 3, wherein the tensioning

means comprises a pivoted element for depressing the yarn in the interval between a pair of spaced guides; and further including means for rendering the motor means inoperative upon movement of said pivoted element beyond prescribed limits in opposite directions.

5. Automatic yarn tension control mechanism, according to claim 3, for a circular knitting machine with sinkers slideable in radial grooves of a 10 sinker ring surrounding a rotary needle cylinder, an encircling band for urging the sinkers toward the needles and a normally stationary cap ring superposed upon the sinker ring, and wherein the rider element is pivoted on the cap ring and 15 bears against the butt ends of the sinkers.

6. Automatic yarn tension control mechanism for a knitting machine having a plurality of independent needles, individually cooperative sinkers spring-urged toward the needles, and means 20 for tensioning a knitting yarn enroute to the needles, said control mechanism including a reversible electric motor for actuating the tensioning device, a rider element bearing against and adapted to be influenced by movement of the sinkers in the 25 event of any tendency of the loops formed by the needles to tighten or slacken, a reversing detector switch arranged to be actuated by the rider element and operative to determine the flow of electric current to the reversible motor in one 30 direction or the other to correspondingly actuate the tensioning means and thereby effect compensatively increase or decrease the tension on the yarn for maintenance of a uniform loop size in individual courses of the fabric produced by 35 the machine.

7. Automatic yarn tension control mechanism for a knitting machine, according to claim 6, wherein the tensioning means comprises a pivoted element for depressing the yarn in the interval 40 between a pair of spaced guides, and further including a pair of limit switches in circuit with the motor adapted to be opened to stop the motor upon movement of said pivoted element beyond prescribed limits in opposite directions.

8. Automatic yarn tension control mechanism 45 according to claim 6, for a knitting machine wherein the tensioning means comprises a pivoted element for depressing the yarn between a pair of spaced guides; and further including a shaft driven through speed reduction gearing from the 50 electric motor, an arm on said shaft coupled to the pivoted element of the yarn tensioning device, and a pair of limit switches in circuit with the motor arranged to be opened by said arm upon movement thereof beyond prescribed limits 55 in opposite directions.

9. Automatic yarn tension control mechanism according to claim 6, for a knitting machine wherein the tensioning means comprises a pivoted 60 element for depressing the yarn between a pair of spaced guides; and further including a shaft driven through speed reduction gearing from the electric motor, and an arm on said shaft coupled to the pivoted element of the yarn tensioning device.

10. Automatic yarn tension control mechanism, 65 according to claim 6, wherein the detector switch comprises a medially pivoted contact with one end thereof normally positioned centrally between a pair of fixed contacts in circuit with the motor, and with the other end thereof bearing against the rider element.
